Primary Examiner — Joseph Kukella*Assistant Examiner* — Lavan M. Amerson(74) *Attorney, Agent, or Firm* — Jones Day(57) **CLAIM**

The ornamental design for a side view mirror actuator as shown and described.

DESCRIPTION

FIG. 1 is a perspective view of the side view mirror actuator;

FIG. 2 is a top view of FIG. 1;

FIG. 3 is a bottom view of FIG. 1;

FIG. 4 is a rear view of FIG. 1;

FIG. 5 is a front view of FIG. 1;

FIG. 6 is a right side view of FIG. 1; and,

FIG. 7 is a left side view of FIG. 1.

Exemplary features are shown in broken lines in the various Figures and form no part of the claimed design.
